UNITED STATES PATENT OFFICE.

PHILIP A. REIDY, OF MALDEN, MASSACHUSETTS.

HORSESHOE-CUSHION.

SPECIFICATION forming part of Letters Patent No. 245,658, dated August 16, 1881.

Application filed April 11, 1881. (No model.)

To all whom it may concern:

Be it known that I, PHILIP A. REIDY, a citizen of the United States, residing at Malden, in the county of Middlesex and State of Massachusetts, have invented a new and useful Horseshoe-Cushion, of which the following is a specification, reference being had to the accompanying drawings.

My invention consists in a cushion or pad formed of one piece of rubber or analogous material to be fastened between the metallic shoe and the hoof, and in such a manner that at the heel the cushion shall intervene directly between the ground and both the hoof and the frog of the foot, the metallic shoe not extending so far back as ordinary horseshoes, and being beveled at the heel to fit a corresponding bevel of the cushion.

In the drawings, Figure 1 is a side view of a horseshoe-cushion embodying my invention, showing the position of the cushion relative to the shoe and the hoof. Fig. 2 is a perspective view of the cushion. Fig. 3 is a perspective view of the cushion in a reverse position from that shown in Fig. 2. Fig. 4 is a perspective view of the metallic shoe.

The metallic shoe A does not extend so far back as ordinary horseshoes, and is beveled at the heel at *a a*, as shown.

The cushion or pad B is formed of one piece, preferably of rubber, though it may be of other material having the qualities of rubber necessary for this purpose. The cushion is of suitable and nearly even thickness where it comes between the main part of the shoe A and the hoof. At the heel the cushion has a web, *b*, to fit or bear against the frog, and the whole rear portion is made of sufficient thickness to fill the space between the ground and the heel of

the foot—that is, of the thickness, or about the 40 thickness, of both the shoe and the cushion at the toe of the foot, so that at the heel the foot shall bear on the cushion, and the latter directly on the ground. The cushion B is beveled at *c c* from the thinner to the thicker part, 45 to fit the bevels *a a* of the shoe A.

The cushion is fastened in place by the horseshoe-nails, which are driven through the metallic shoe in the ordinary manner, and through that part of the cushion between the shoe and 50 the hoof.

These cushions are especially useful for horses having sore feet, and by giving a good and elastic bearing at the heel the horses wearing them will tread more easily and securely; 55 also, on account of there being rubber or analogous material at the heels, "shoe-boils," so called, which are caused on some horses by the hard sharp ends of ordinary horseshoes, will not be formed. 60

I claim as my invention—

1. In combination with a horseshoe short at the heel so as not to extend as far back as the hoof, a cushion formed (as one piece) of rubber or analogous material, having a thinner part 65 to come between the metallic shoe and the hoof and a thicker part to come between the ground and both the frog and heel of the hoof, substantially as and for the purpose specified.

2. The combination, with a horseshoe shortened at the heel and having the bevels *a a*, of a cushion having the thinner and thicker parts, 70 the web *b*, and beveled to fit the shoe, substantially as described.

PHILIP A. REIDY.
